UNITED STATES PATENT OFFICE.

TRUMAN W. POST, OF PROVIDENCE, RHODE ISLAND, AND CLARENCE B. DES JARDINS,
OF TOLEDO, OHIO, ASSIGNEES TO ELECTRIC AUTO-LITE CORPORATION, OF TOLEDO,
OHIO, A CORPORATION OF DELAWARE.

HEADLIGHT.

1,267,691.

Specification of Letters Patent. Patented May 28, 1918.

Application filed September 14, 1917. Serial No. 191,404.

To all whom it may concern:

Be it known that we, TRUMAN W. Post and CLARENCE B. DES JARDINS, citizens of the United States, residing at Providence and Toledo, in the counties of Providence and Lucas and States of Rhode Island and Ohio, respectively, have invented certain new and useful improvements in Headlights, of which we declare the following to be a full, clear, and exact description.

This invention relates to improvements in headlights and more particularly to headlights which are provided with a pivotally mounted reflector which may be tilted to throw the beam of light downwardly upon the ground when approaching another vehicle or a pedestrian so as to avoid the objectionable glare.

The principal object of our invention is to provide a simple and efficient means for stiffening and reinforcing the front edge of the reflector and at the same time providing the pivotal mounting for the reflector.

A further object of our invention is to provide simple and efficient means which will afford a pivotal mounting for the reflector and will, at the same time, stiffen the front edge of the reflector and retain a transparent covering over the front of the reflector so as to prevent moisture gaining access to the reflecting surface, so as to tarnish the same.

Further objects, and objects relating to economies of manufacture and details of construction, will definitely appear from the detailed description to follow.

We accomplish the objects of our invention by the devices and means described in the following specifications. Our invention is clearly defined and pointed out in the appended claims.

A structure constituting a preferred embodiment of our invention is illustrated in the accompanying drawings, forming a part of this specification, in which:

Figure I is a vertical, sectional view, through a headlight embodying our invention.

Fig. II is a transverse, vertical, sectional

view, taken substantially on the line II-II 50 of Figs. I and IV.

Fig. III is an enlarged, detail, fragmentary view, partly in section and partly in front elevation, showing one of the trunnions for the reflector and its bearing. 55

Fig. IV is a detail, sectional view, taken through the edge of the reflector and showing the reinforcing bead, the clamping ring and a portion of the transparent pane covering the front of the reflector. 60

In the drawings, similar reference numerals refer to similar parts throughout the several views, and the sectional views are taken looking in the direction of the little arrows at the ends of the section lines. 65

Considering the numbered parts of the drawing, we have shown a headlight embodying a casing 10, the front of which is closed by lens 11 carried by a ring 12 in the usual manner. A reflector 13 is pivotally 70 mounted within the casing 10 and carries a socket 14, which receives the electric light bulb 15, said socket being connected by the wires 16 with the connector 17 carried by the rear of the casing 10. An annular channel 19 which faces forwardly is formed in the forward edge of the reflector 13 and a packing ring 20 of wicking or other suitable material is disposed in said channel. Said packing ring may be held in place by shellac if desired. Beyond the channel 19 the material from which the reflector is formed is bent forwardly and then rearwardly around a pair of semi-circular reinforcing wires 21, which, together, form a 85 continuous annular reinforcing bead, serving to preserve the true parabolic shape of the reflector since the free edge of the reflector will always be maintained circular.

Openings are provided in the bead 22 at 90 diametrically opposite points and the opposite ends of said reinforcing wires are bent laterally at 26 and extend through said openings, forming the trunnions for the reflector. The reflector is closed by the 95 transparent pane of glass 18 which rests against the bead 22 and the packing ring 20, as clearly shown in Figs. I and IV, and

this pane of glass is retained in place by the split channel-shaped clamping ring 23 which embraces the bead 22 and the periphery of the pane 18 and is provided with a pair of radially extending ears 24, through which a bolt 25 passes to draw the parts of the ring together.

The ring 23 is provided with diametrically opposite openings through which trunnions 26 extend. Spring strips 27, which are arched somewhat, are secured at their ends to the casing 10 by the rivets 28 and carry bearing blocks 29 in which the trunnions 26 of the reflector are journaled. This construction affords a spring bearing for the reflector trunnions. A clamp 30 embraces the socket 14 between the reflector 13 and the casing 10 and is connected to a wire 31 which passes out through a tube 32 carried in a boss 33 secured to the casing 10, the tube 32 being held against movement by the set screw 34. The wire 31 may be manipulated in any suitable manner to tilt the reflector on its trunnions.

From the description of the parts given above, the operation of this device should be very readily understood. It will be seen that the reinforcing wires 21 which form the reinforcing bead to stiffen the front edge of the reflector so as to keep it in shape, are extended to form the trunnions for the reflector. This makes a very simple construction and one which can be produced very cheaply. It will be seen that in this construction the reflector trunnions are carried by the reflector itself and not by the clamping ring which secures the pane of glass 18 to the front of the reflector. The reflector may be formed together with the trunnions, after which the pane of glass may be applied to the front of the reflector and secured in place by the clamping ring 23 and the whole reflector may then be mounted in its bearings. The bearing blocks 29 are spring-mounted and will yield sufficiently to permit the insertion of the trunnions.

We have shown a simple means for manipulating the reflector so as to tilt it upon its axis, but this tilting mechanism forms no part of our invention, which has to do with the construction of the reflector trunnions, the stiffening for the front edge of the reflector, means for securing the transparent covering for the reflector in place and the spring trunnion bearings.

We are aware that the particular embodiment of our invention, which we have here shown, is susceptible of considerable variation without departing from the spirit thereof, and, therefore, we desire to claim our invention broadly, as well as specifically, as indicated by the appended claims.

Having thus described our invention,

what we claim as new and desire to secure by Letters Patent, is:

65

1. A device of the class described, comprising the combination of a casing, provided with a pair of diametrically opposite trunnion bearings; a reflector within said casing; a pair of semi-circular reinforcing wires disposed adjacent the front edge of said reflector; the opposite ends of each of said wires being bent laterally and journaled in said bearings; and the front edge of said reflector being rolled around said reinforcing wires to form a circular stiffening bead.

2. A device of the class described, comprising the combination of a casing; a reflector within said casing, the forward edge of said reflector being rolled back to form a stiffening bead; a pair of semi-circular reinforcing wires disposed within said bead, one end of each of said wires being bent laterally and extending through said bead to form reflector trunnions diametrically opposite each other; and bearings for said trunnions carried by said casing.

3. A device of the class described, comprising the combination of a casing; a reflector within said casing, the forward edge of said reflector being rolled back to form a stiffening bead; a pair of semi-circular reinforcing wires disposed within said bead, one end of each of said wires being bent laterally and extending through said bead to form diametrically opposite trunnions for said reflector; a transparent closure for the front of said reflector; a clamping ring embracing said bead and the periphery of said closure to secure said closure in place, said clamping ring being provided with openings through which said trunnions pass; and bearings for said trunnions carried by said casing.

4. A device of the class described, comprising the combination of a casing; a reflector within said casing, the forward edge of said reflector being rolled back to form a circular stiffening bead; a reinforcing wire disposed within said bead; a reflector trunnion integral with said wire; and a bearing for said trunnion carried by said casing.

5. A device of the class described, comprising the combination of a casing; a reflector within said casing, the front edge of said reflector being rolled back to form a stiffening bead; a reinforcing wire in said bead provided with a trunnion integral therewith; a spring strip carried by said casing; and a trunnion bearing mounted on said spring strip.

6. A device of the class described, comprising the combination of a casing; a reflector within said casing; the forward edge of said reflector being provided with a

stiffening bead; a pair of diametrically opposite trunnions carried by said bead; a transparent closure for the front of said reflector; a clamping ring embracing said bead and the periphery of said closure to secure said closure in place, said clamping ring being provided with openings through

which said trunnions pass; and bearings for said trunnions carried by said casing.

In testimony whereof we affix our signatures.

TRUMAN W. POST,
CLARENCE B. DES JARDINS.
